United States Patent Office.

JOSEPH M. HOADLEY, OF BIRMINGHAM, CONNECTICUT.

Letters Patent No. 76,916, dated April 21, 1868; antedated April 8, 1868.

IMPROVEMENT IN CROCHET-NEEDLES.

The Schedule referred to in these Letters Patent and making part of the same.

TO ALL WHOM IT MAY CONCERN:

Be it known that I, JOSEPH M. HOADLEY, of Birmingham, in the county of New Haven, and State of Connecticut, have invented a new and improved "Crochet-Needle;" and I do hereby declare that the following is a full, clear, and exact description thereof, which will enable others skilled in the art to make and use the same, reference being had to the accompanying drawings, forming part of this specification.

This invention consists in making a holder for crochet-needles of the same wire as that from which the needles are produced, either as a continuation thereof, or distinct and separate therefrom, with the needle arranged to slide upon the same, and thus be brought into position for use; where, by the spring to the tempered wire, it is held, whether drawn more or less out of its holder.

In the accompanying plate of drawings, my improvement in crochet-needles is illustrated—

Figure 1 being a side view of the same and its holder, and

Figure 2 a section, taken in the plane of the line $x\ x$, fig. 1.

Similar letters of reference indicate like parts.

A, in the drawings, represents a crochet-needle, which, in general shape and form, is similar to the ordinary crochet-needles, but, in its manufacture, is made directly from tempered wire, in lieu of wire not tempered, but tempered after the needle is made.

B, the holder for the needle, which is made from tempered wire. This needle slides upon the holder B, and, as it has a spring, it secures and holds it in whatever position it may be set.

What I claim as new, and desire to secure by Letters Patent, is—

1. The holder B, for crochet-needles, formed, with the needle A, from the same piece of tempered wire, as herein shown and described.

2. The holder B, for crochet-needles, formed of tempered wire, upon which the needle is arranged to slide and be held in position by the elasticity of said holder, as herein shown and described.
